UNITED STATES PATENT OFFICE.

PHILO J. ORMISTON, OF PHILADELPHIA, PENNSYLVANIA, ASSIGNOR TO
JAMES BERNARD WILSON, OF SAME PLACE.

DESIGN FOR A SCISSORS-SHARPENER.

SPECIFICATION forming part of Design No. 28,187, dated January 18, 1898.

Application filed November 18, 1897. Serial No. 659,047. Term of patent 3½ years.

To all whom it may concern:

Be it known that I, PHILO J. ORMISTON, a citizen of the United States, residing in the city and county of Philadelphia, State of Pennsylvania, have invented and produced a new and original Design for a Scissors-Sharpener, of which the following is a specification, reference being had to the accompanying drawings, forming part thereof.

10 The leading feature of my design for scissors-sharpener is a block having in the face thereof a shoulder and a depressed face and an inclined blade on said block adjacent to said shoulder.

15 Figure 1 represents a perspective view of a scissors - sharpener embodying my design. Fig. 2 represents a section thereof on line *x x*, Fig. 1.

In the drawings, A designates a block, on the face of which is the inclined blade B, the 20 inclined shoulder C, adjacent to the inner end of said blade, and the depressed face D, the latter being somewhat ogee shape, said shoulder and blade forming an acute angle.

E designates a screw whose head overlaps 25 the adjacent edges of the blade.

What I claim is—

The design for a scissors-sharpener substantially as shown and described.

PHILO J. ORMISTON.
